UNITED STATES PATENT OFFICE.

CHARLES D. OLAND, OF CENTRALIA, ILLINOIS, ASSIGNOR TO ELECTRIC-PNEUMATIC SKID CO., OF CENTRALIA, ILLINOIS.

AUTOMATIC CONTROL FOR CAR RETARDERS.

Application filed December 21, 1925. Serial No. 76,810.

This invention relates to new and useful improvements in car retarding mechanisms, and particularly to means for automatically controlling the same.

5 The principal object of the invention is to provide a mechanism by means of which the retarder is automatically actuated in accordance with the speed of the car.

10 Another object is to provide a device of this character wherein a mechanism is set in motion, and then permitted to move toward normal position, together with train or car actuated means for checking or stopping this movement toward normal position 15 in accordance with the speed of the car.

Another object is to provide an automatic car retarding mechanism which is adapted to be set in position for engagement with the wheels of a car, and which is maintained 20 in such position by the car.

25 A further object is to provide a mechanism which is automatically operated by a car and by means of which the retarding elements are set to engage the wheels of the car at a certain pressure, commensurate with the speed of the car, and wherein such pressure is maintained by means actuated by the car.

30 Other objects and advantages will be apparent from the following description when taken in connection with the accompanying drawings.

In the drawings:

35 Figure 1 is a side elevation of a portion of a railway showing the invention applied thereto.

Figure 2 is an enlarged side elevation of the circuit closing switch.

40 Figure 3 is a front elevation of the same.

Figure 4 is a vertical sectional view on the line 4—4 of Figure 2.

45 Figure 5 is a side elevation of the auxiliary rotary switch.

Figure 6 is a front elevation of the same.

Figure 7 is a sectional detail view on the line 7—7 of Figure 5.

50 Figure 8 is a horizontal sectional view on the line 8—8 of Figure 2.

Figure 9 is a plan view of a portion of a railway, the retarding shoes, and the means for regulating the pressure of the latter.

55 Figure 10 is a vertical sectional view on the line 10—10 of Figure 2.

Referring particularly to the accompany-

ing drawings, 10 represents a portion of a railway, in connection with which the present invention is used, such railway being a portion of a train yard hump.

60 In the making up of trains, cars are per-

mitted to coast from the hump to the places where the trains are to be made up. These cars gain considerable momentum, and if

not checked in their speed, before reaching the trains, will cause great damage. Vari-

ous devices have been used to retard the speed of the cars, but these devices are oper-

ated from towers, thus requiring the serv-

ices of a number of men. These devices in-

clude elements arranged along the rails, 70

which are motor operated into frictional contact with the wheels of the cars, as said cars pass along the track. These track ele-

ments must be moved so as to contact with the wheels at greater or less pressure, in ac-

cordance with the speed of the traveling cars, 75

to bring the cars down to the desired safe speed. Heretofore these track elements were controlled from towers, manually, and it

is the particular object of the present inven-

tion to actuate these track elements automati-

cally, through mechanism actuated by the 80

passing cars.

Mounted adjacent the railway is a support 85

11, carrying thereon a shaft 12, and loosely mounted on the shaft is a disk 13, having a hub 13'.

On one end of the shaft is fixed a crank arm 14, to the outer end of which is pivotally connected the intermediate por-

tion of a link 15, said link extending along 90

the railway, for suitable distances in both directions, from said shaft. Fixed on one side face of the disk 13 is a guide eye 16, and

slidable through this eye is a pin 17, said pin

having a head 18 on one end and having its 95

other end arranged to enter an opening in the shaft 12, whereby to couple the disk and

shaft together for simultaneous rotation, as

will be explained later herein. Secured to

the said side of the disk 13 is a bevel gear 20, 100

which meshes with a bevel gear 21, on the

adjacent end of a horizontal shaft 22, which

shaft is properly supported in a bearing on

the support 11. The other end of the shaft

22 carries a similar bevel gear 23, which

meshes with the bevel gear 24 loosely mount-

ed on the vertical governor shaft 25. This

bevel gear 24 includes a housing 24', within

which is mounted the ratchet wheel 26, fixed

on the shaft 25. The gear 24, and its hous-

ing 24' are supported against downward movement on the shaft 25 by means of the fixed collar 25', on said shaft. By this construction, it will readily be seen that when the disk 13 is rotated in a clockwise direction, the gear 24 will be loosely turned in one direction on the shaft 25, the pawl idly sliding over the teeth of the ratchet wheel 26, but that when the disk is rotated in a counter-clockwise direction, the pawl 26' will engage the teeth 26 and rotate the shaft 25 in the opposite direction. On the upper end of the shaft 25 are the ball governor arms 11'. Secured on the support 11, adjacent the side of the disk 13, is an arcuate track 27, on which the before-mentioned head 18, of the pin 16, is arranged to slide, a portion of the lower end of the track being free, and flexible, and overlying a short inclined-track section 28. A spring 17', on the pin 17, serves to normally urge the pin against the track 27. Secured to the peripheral face of the disk 13, and projecting radially therefrom, are the lugs 29, four being shown in the drawings, although a larger or smaller number may be used, as the conditions require, said lugs being properly insulated from the disk, in any desired manner. Connected to each of the lugs 29 is a wire 30, which leads to retarder controlling mechanism, at 31, in Figure 1, which will later be described. A motor spring 13' has its inner end secured to the hub 12', while its outer end is secured to the support 11, such spring serving to rotate the disk 13 in a counter-clockwise direction. Secured at its lower end to the support 11, is a curved arm 32, said arm extending upwardly in concentric relation to the periphery of the disk 13, for a suitable distance, and then being approximately straight and horizontal, the upper terminal being provided with an armature disk 33, adapted to be attracted by the core of the electromagnet 34. This electromagnet is supplied with current from the battery 55, by means of the wires 53, 54, and 56. Fixed to the inner face of the arm 32, adjacent the upper end of the curve thereof, is a lug 35, and connected to the lower fixed end of the said arm is a wire 36, said wire extending to the same point as the wires 30. Fixed on the arm 32, above the curved portion thereof, and extending vertically therefrom, is a trip arm 37, which lies in the path of the wheels of a car, to be engaged and moved thereby. At a suitable distance from the support 11, and adjacent the rail of the railway 10, is a vertically disposed, centrally pivoted trip arm 38, which is adapted to be engaged and rocked by the wheels of a car leaving the hump. The lower end of this trip arm 38 is pivotally connected with the adjacent end of the before-mentioned link 15, whereby, when the car wheel rocks said arm, motion is imparted, through the link 15, to

the arm 14, and due to the interlocking of the shaft 12, and the disk 13, the said disk will be rotated in a clockwise direction. As the disk 13 turns the lugs 29 will be successively moved upwardly above the lug 35, 70 while at the same time maintaining the shaft and disk in cooperative relation, through the engagement of the head of the pin 17 on the track 27. Should the disk be rotated sufficiently to permit the head of the pin to leave 75 the upper end of the track, the spring 17' will cause the pin to be projected outwardly, so that the head will lie outwardly of the track. As soon as the first wheels of the car have rocked the trip arm 38, and have passed 80 thereover, the motor spring 13', which has been wound by the forward, or clockwise movement of the disk 13, will unwind whereby to rotate the disk in a retrograde, or anti-clockwise direction, thus restoring the arm 85 38 to a position for engagement by the next wheel of the car. As the disk 13 rotates in an anti-clockwise direction, the head 18, of the pin 17, will ride on the lower face of the track 27, until it reaches the flexible end of 90 said track, when said head will flex the track end, and ride up on the short track section 28 with the result that said head will then be in a position to ride on the upper face of the track 27, upon rotation of the disk 13 95 in its clockwise direction. When the head of the pin 17 leaves the upper end of the track 27, and rides on the lower face of said track, the other end of the pin will be released from the opening in the shaft 12, with 100 the result that the disk 13 is free to rotate on the shaft, while at the same time the shaft may be freely rotated within the disk, in the event that said disk is held against retrograde rotation by engagement of one of its 105 lugs 29 with the lug 35. When, however the head of the pin 17 has passed the flexible end of the track, and has again engaged on the upper face thereof, the pin will be in a position to be urged into the opening of the 110 shaft 12, to again couple the shaft and disk. A second support 40 is mounted adjacent the point 31, of the railway, and carried by said support is a shaft 41, on which is rigidly mounted a disk 42, of a size similar to 115 the disk 13, and having the bevel gear 41' on its side face, which meshes with the bevel gear 57, on the horizontal shaft 58, which is supported on the support 40. A motor spring 44 has its inner end secured to the hub 42', of the disk 42, and its outer end secured to the support 40, as clearly seen in Figure 6. The other end of the shaft 58 carries a bevel gear 60' which meshes with the gear 59, mounted on the vertical governor shaft 43, said gear 59 being provided with the casting 61', and otherwise being of identical construction to that of the gear 24, and co-operating with the shaft 43 in the same manner. In this connection, it might be 120 125 130

said that the Figures 8 and 10, while being details of the gear 24, will serve as details of the gear 59, as well. Fixed on the shaft 41 is a radially extending arm 46 which is pivotally connected with the adjacent end of the before-mentioned link 15, whereby upon rocking of the trip arm 38, by the wheel of a passing car, both the disk 13, and the disk 42, will be rotated. Fixed on the support 40 is a radially extending arm 52, and connected to said arm, and to one end of the coil of the electromagnet 34, is the wire 53, while the wire 56 is connected to the other end of the coil of said magnet, and to one side of the battery 55. Secured to, and extending around a portion of the periphery of the disk 42, is a metal plate or strip 51, which is adapted to be engaged by the contact member 52', which is carried by said 20 arm 52, and connected to said plate or strip 51 is the wire 54, which is also connected to the other side of the battery 55. Thus, when the disk 42 is rotated in a clockwise direction, the plate 51 will be brought under the contact member 52', so that the electromagnet 34 will be energized, and in the event that the car wheel has engaged the trip arm 37, and flexed the arm 32 sufficiently to bring the armature 33 into close proximity to the 25 said magnet, said armature will be held by the attraction of the magnet, with the result that one or another of the lugs 29 will lie above the lug 35, whereby to prevent the disk 13, from retrograde rotation. The shaft 12, can, however, rotate in a retrograde direction, because of the fact that the pin 17 will always have been disengaged from the opening in said shaft by the operation of 38, thereby permitting the shaft 41, 30 and the disk 42 to turn backwardly, under the influence of the spring 44. Secured to one side face of the disk 42 is an arcuate strip 45, formed with a series of ratchet teeth. Secured to, and rotatable with the shaft 41, is a vertically extending trip arm 47, which is adapted to be engaged and rocked by the wheels of a passing car. A coil spring 50, connected to the arm 47, and to the support 40, yieldably holds the arm in 35 vertical position, and tends to restore the same to such position when released from the car wheel. A spring pressed pivoted pawl 48 is mounted on the arm 47, and is arranged to engage with the ratchet teeth of the strip 45, whereby, upon rocking of said arm, by the wheel of a car, the said pawl will engage a tooth of the strip and rotate the disk 42 in a clockwise direction, thus bringing the contact plate 51 into engagement with the contact member 52', to close the circuit through the battery 55, and the electromagnet 34. This energizes the magnet 34, and causes the armature 33 to be attracted thereto, so that the arm 32 will be held in position to maintain the disk 13 40 against retrograde rotation. Fixed on the support 40, in a vertical position, is an arm 49, which is engaged by the pawl, to lift the same out of engagement with the teeth of the strip 45, when the arm 47 has moved back to normal position, whereby to permit the motor spring 44 to rotate the disk 42 in a counter-clockwise direction. It will be noted that a portion of the strip 45 extends toward the right, beyond the arms 47 and 49, when the arm 47 is in a vertical position, so that when said arm is again moved forwardly, by the car wheel, the pawl will readily engage with the teeth of said strip, for the purpose of again advancing the disk in a clockwise direction.

The disk 13, in conjunction with the arm 32, forms a rheostat, while the elements 51-52 form a switch.

Thus the movement of the arm 38, by the first wheels of a car, sets the entire mechanism in condition to urge the shoes 39 for the maximum pressure against the car wheels. If the car is moving at such a high speed as to reach and trip the arm 37, before the disk 13 can retrograde back toward normal position, such disk will be locked in its advanced position, while at the same time the disk 42 will be advanced to energize the magnet 34 to maintain the flexible arm 32 in its locking position. The governors operate to prevent the too rapid retrograde rotation of the disks, so that if the car is moving at a speed above normal, such car will have passed between the retarding shoes 100 before the circuit is broken between the contact 52 and strip 51, and the required pressure of the shoes is brought to bear on the car wheels to check its speed. As each successive wheel of the car strikes the arm 47, the disk 42 is intermittently moved forward 105 to maintain engagement between the members 51 and 52, and maintain the magnet 34 energized, whereby to hold the arm 32 and keep the circuit to the shoe actuating mechanism closed, and the pressure of the shoes constant until the car has passed from between the shoes.

Referring particularly to Figure 9, of the drawings, the retarder shoes 39, are arranged inwardly and outwardly of the rails 10. Connected to the rod 62, are the corresponding ends of one of the outer shoes and one of the inner shoes. Connected to the rod 63 is the other end of the other outer shoe, and the corresponding end of the other inner shoe. Adjacent the railway is a centrally pivoted, and longitudinally extending rocker arm 64, and pivotally connected to one end of this arm is one end of the rod 62, while the rod 63 is pivotally connected to the other end of the arm. A piston rod 58 is pivotally connected to the arm 64 at the same point at which the rod 63 is connected thereto, said piston rod operating a piston (not shown) within 110

120

125

130

the air cylinder 57. An air chest 59' is connected with the opposite ends of the cylinder 57 by means of the pipes 65 and 66, while a supply line 67 is connected to the said chest for supplying compressed air from a suitable source, not shown. An electro-pneumatic valve 60 is associated with the air chest for controlling the flow of air from the chest to the pipes 65 and 66. The disk 13 is shown diagrammatically, and includes the lugs 29, associated with the flexible arm 32 with its single lug 35. The wire 36 leads from the arm 32 to one side of the battery 68, while a wire 69 leads from the other side of the battery to the electro-pneumatic valve 60. Connected to the valve 60 is a wire 30 which leads to the lowermost of the lugs or pins 29, of the disk 13. Tapped in this wire 30 are stationary contacts 70 with which are adapted to engage the switch arms 61. The elements 57, 58, 59, 60, 61, 65, 66, 67, and 70 are all parts of the mechanism illustrated and described on page 393 of Railway Age, of March 2, 1926, vol. 80, No. 6. From each of the switch arms 61 a wire 30 leads to one of the pins or lugs 29 of the disk 13. When the disk 13 is rotated so as to bring its lowermost pin 29 above the pin or lug 35, the contact between said lugs or pins completes the circuit through the battery 68 and the electro-pneumatic valve 60, by means of the wires 30 and 36, with the result that said valve is moved to permit a certain amount of air to pass into the cylinder 57, thus forcing the piston toward the right, of Figure 9, and setting the retarder shoes 39 at the proper distance from the rails 10, to exert the required amount of friction on the car wheels, to check the speed of said car. Assuming that a car is traveling from the hump at a high rate of speed, say six or eight miles per hour, and has engaged the arm 38, to rotate the disks 13 and 42, and has closed the circuit of the battery 55, to energize the magnet 34, the car will have sufficient time in which to reach and move the arm 37 before the disks can retrograde back to normal position, under the influence of the motor springs 13' and 44, thus causing the armature of the arm 32 to be attracted to and be held by the magnet 34, so that one of the lugs 29 will be held by the lug 35. The particular lug 29, held by the lug 35 corresponds to the pressure required of the shoes 39 to slow down the car to the proper and safe speed. Furthermore, the speed at which the car is traveling will permit the car to engage the arm 47 before the disk 42 can rotate backwardly under the influence of the motor spring 44, to a sufficient distance to break the circuit at 51—52, with the result that the arm 47 is swung forwardly so that its pawl engages with the teeth 45, in advance of the stop arm 49, and rotates the disk forwardly again, so as to maintain contact between

members 51 and 52, and the magnet 34 energized. Should the car be traveling at a slower speed, the disk 13 will rotate backwardly so that when the circuit of the battery 55 is closed by the contact of 51 with 52, the lug 29, so engaged by the lug 35, will correspond to a lesser pressure required of the shoes 39. However, the car strikes the arm 47 so as to rotate the disk 42 whereby to maintain the circuit of the battery 55 closed, whether the car is traveling at a high rate of speed, or at a normal rate.

The distance between the arms 38 and 37 is such that the car must strike the latter before the disk 13 can return to normal position, or return out of the position corresponding to the pressure required for the shoes 39, for a predetermined rate of speed of the car. Thus the distance is reckoned from the time standpoint, rather than from actual linear distance, while of course it is calculated that the car will travel a certain distance, within a given time, at a certain rate of speed. The arm 47 is so placed, with respect to time-distance, from the arm 38, that the car, if traveling above the normal speed, will strike the arm 47 before the circuit is broken at 51—52. Thus, with the exception of the instance where the car is traveling from the hump at the required or normal or safe speed of four miles per hour, the arms 38, 37, and 47 will be successively struck and rocked before either disk 13, or the disk 42 can retrograde back beyond a position corresponding to that required to apply the proper degree of pressure of the shoes 39. In the first instance, that where the car is traveling at the excessive speed, which requires the full pressure of the shoes 39, the engagement of the lowermost lug 29, with the lug 35, closes the circuit through the battery 68, by means of the wires 36, the extreme left-hand wire 30, the first switch 61, to the right in Figure 9, the electro-pneumatic valve 60, and the wire 69. If the car is traveling at the normal speed, it will not reach the arm 37 in time to prevent the disk 13 rotating back to normal or engage the arm 47, to maintain the circuit of the battery 55, with the result that the disk 42 rotates back to normal position, and nothing happens, as the shoes 39 do not move into engagement with the car wheels, because the speed of the car does not need to be checked.

When the car rocks the arm 38, it causes the rotation of the disks 13 and 42, so that one of the lugs 29 will lie above the lug 35, and the plate 51 will be in contact with the element 52', while the toothed strip will be projected beyond the arm 47. The engagement of the elements 51 and 52' closes the circuit to the battery 55 to energize the electromagnet, ready to attract and hold the armature of the arm 32, should the car move

the arm into close proximity thereto. The rocking of the arm 47 merely maintains the circuit of the battery 55 closed to prevent the disk 13 rotating back to normal position, in 5 the event that the car travels fast enough to operate said arm before the said disk can retrograde. The retarding action of the shafts 25 and 43, due to the weight of the 10 governor balls, serves to prevent the disks returning to normal position too rapidly, and thus permits the car to reach the successive 15 trip arms in time to set the various devices in position to maintain the retarder shoes in position for pressure against the car wheels.

15 What is claimed is:

1. The combination with car retarder shoes and the mechanism for applying same at different pressures including an electric circuit, of an automatic control for said 20 mechanism including a car actuated selective switch in the circuit, for regulating the current to and thereby the operation of the applying mechanism in accord with the speed of the car, means actuated by the car 25 for maintaining the switch in its operative position, and car actuated means for holding the maintaining means until the car has been checked by the shoes.

2. The combination with retarder shoes 30 and the mechanism for applying said shoes at different pressures including an electric circuit, of an automatic control for said mechanism including a car actuated selective switch in the circuit for regulating the amount of current supplied to the mechanism whereby to apply the shoes at the pressure required to check the car, means initially actuated by the car for maintaining 35 the switch in its operative position, and means subsequently actuated by the car as said car passes the retarder shoes, for holding the initially actuated means until the car has been checked by the shoes.

3. The combination with retarder shoes 40 and the mechanism for applying said shoes at different pressures including an electric circuit, of an automatic control for said mechanism including a selective switch in the circuit for setting the mechanism to apply the shoes at a pressure required to check the speed of the car, means initially operable by the car for holding the setting means in such position, and means operable by the car for maintaining the holding means until 45 the car has passed the shoes.

4. The combination with retarder shoes 50 and the mechanism for applying same at different pressures including an electric circuit, of an automatic control for the mechanism including an electric circuit, a selective switch in the circuit of the applying mechanism actuatable by a passing car for setting the mechanism to apply the shoes at a pressure required to check the speed of 55 the car, means in the control circuit for

holding the first circuit closer in circuit closing position, and car actuated means for maintaining the control circuit closed while a car is passing.

5. The combination with retarder shoes 60 and the mechanism for applying same at different pressures including an electric circuit, of an automatic control for the mechanism including an electric circuit, a circuit closer in the circuit of the applying mechanism for setting the shoes at a pressure commensurate with the speed of the car, a switch and an electro-magnetic means in the control circuit for holding the circuit closer in shoe applying position, trip means operable by the car for initially setting the circuit closer in a position to actuate the applying mechanism commensurate with the speed of the car and for closing the said switch, and car actuated means for maintaining the switch closed while the car is 65 passing the retarder shoes.

6. The combination with car retarder shoes and the mechanism for applying the same including an electric circuit, of an 70 automatic control for the applying mechanism including an electric circuit, an electro-magnetic means in the control circuit, a rheostat in the circuit of the applying mechanism including a rotatable member 75 and a flexible arcuate member, a switch in the circuit of the control, car actuated means for simultaneously turning the rotatable member into operative position for applying the shoes at a pressure commensurate with the speed of the car and for closing the switch, the said flexible member being adapted to be actuated by the car into holding engagement with the rotatable member and into the field of said electro-magnetic 80 means, and car actuated means for maintaining the switch in closed position.

7. The combination with car retarder shoes and the mechanism for applying said 85 shoes at different pressures including an electric circuit, of an automatic control for the applying mechanism including an electric circuit, a selective switch in the circuit of the applying mechanism comprising a rotor and a flexible member movable toward and away from the rotor, car actuated means for rotating the rotor, an electro-magnetic means in the control circuit, and car actuated means for moving the flexible member into holding engagement with the 90 rotor and into the magnetic field of the electro-magnetic means, and a switch in the control circuit initially closed by the approaching car and subsequently maintained in closed position by the car as the latter passes 95 between the shoes.

8. The combination with car retarder shoes and the mechanism for applying the same at different pressures including an electric circuit, a selective switch in the cir- 100

- cuit comprising a rotor having contact elements thereon, and a flexible arcuate member having a single contact and movable toward and away from the rotor, car actuated means for rotating the rotor to position one of its contact elements to be engaged by the single contact, a local circuit, car actuated means for flexing the flexible member toward the rotor, whereby to engage its contact with said contact of the rotor to prevent retrograde rotation of the rotor, and car actuated means for holding the flexible member in rotor engaged position until the car has left the shoes.
- 5 10 15 20 25 30 35 40 45 50 55
- 15 9. The combination with a car retarder mechanism including an electric circuit, of a switch in the circuit including a rotor having a plurality of contact elements and a flexible arcuate member having a single contact element and movable toward and away from the rotor, car actuated means for rotating the rotor to position one of the contact elements thereof to be engaged and held by the single contact of the flexible member, car engaged means on the flexible member for flexing the member to engage its contact element with one of the contact elements of the rotor to prevent retrograde rotation of the latter, and electro-magnetic means operable by the car as the car passes the shoes for holding the flexible member engaged with the rotor until the car has passed the shoes.
10. The combination with a retarder mechanism including an electric circuit, of a selective switch in the circuit including a rotor having a series of contacts and a flexible arcuate member having a single contact and adapted to be flexed toward and away from the rotor, a control circuit including an electro-magnet and a switch, a car actuated trip, a rod connected with said rotor and said switch and operable by said trip, whereby to initially set the rotor in position for engagement by the single contact commensurate with the speed of the car and for closing said switch to energize the electro-magnet, said flexible member being arranged to be moved by the car into the field of the electro-magnet, and means on the switch operable by the car while passing through the retarder for maintaining the flexible member in such position until the car has passed from the retarder.

In testimony whereof, I affix my signature.

CHARLES D. OLAND.
